UNITED STATES PATENT OFFICE.

ERHARD ALLEN, OF DAYTON, OHIO, ASSIGNOR TO THE DAYTON DISPLAY FIXTURE COMPANY, OF DAYTON, OHIO, A CORPORATION OF OHIO.

DISPLAY STAND.

Application filed January 15, 1925. Serial No. 2,528.

This invention relates to new and useful improvements in display stands.

It is the principal object of this invention to provide an attractive, light and spacious display stand which may be economically manufactured. A large number of its parts are formed from sheet metal as stampings which are adapted to be easily assembled, and in many instances spot-welded together, 10 to form with the other parts a compact, strong and neat appearing stand for the display of fruit, vegetables and other articles. The stand has an ornamental balance which is pleasing to the eye, and the small number 15 of nuts, bolts and fastening elements which it contains are so concealed from view as not to detract from its ornate appearance.

In the accompanying drawings, Figure 1 is a perspective view of the display stand. Figure 2 is a sectional view taken on the line 2—2 of Figure 1, through the box and basket holder. Figure 3 is an end view of the display stand, showing the arrangement 25 of the supporting members. Figure 4 is a sectional view taken through the rim of the top tray on the line 4—4 of Figure 1. Figure 5 is a sectional view taken through the rim of the intermediate and lower trays on the lines 5—5 and 5—5 of Figure 1. Figure 30 6 is a sectional view on the line 6—6 of Figure 1, showing the method of supporting the box and basket holder. Figure 7 is a sectional view taken on the line 7—7 of Figure 6, showing the method of supporting the 35 box and basket holder. Figure 8 is a perspective view of one of the transverse brackets for supporting the trays. Figure 9 is a sectional view taken on the line 9—9 40 of Figure 8, showing the method of attaching the brackets to the vertical supports. Figure 10 is a detail view, partly in section, showing the method of locking the transverse partitions together at a longitudinal 45 partition. Figure 11 is a perspective view showing the method of assembling the vertical standards and the longitudinal and transverse partitions. Figure 12 is a side elevational view showing the longitudinal 50 support under the top shelf. Figure 13 is a sectional view taken on the line 13—13 of Figure 12. And Figure 14 is a view of the side of a tray showing the perforations therein.

55 Referring to the accompanying drawings

for a detailed description of the form of embodiment of my invention illustrated therein, the numerals 1, 1 designate two bottom angle members mounted at each end upon a caster 2. The stem of each caster projects upwardly through a hole formed in the bottom of its angle member 1, and a hole in the foot portion 3 of a bracket 4 which is turned at different angles to form with a similar bracket on the other side 60 of the stand, an arched support for the box and basket holders to be hereinafter described. The upper ends of the caster stems are threaded to receive nuts 5 by which the casters and the feet 3 of the bracket members 4 are firmly secured to the ends of the angle members 1. (See Figures 1 and 6.)

Each bracket member 4 has a downwardly inclined straight middle part 6, whereby such parts 6 on the two brackets on each 75 side of the display stand may support a box and basket holder 7. Each holder 7 preferably comprises a rectangular frame divided into basket receiving spaces by a series of transverse angle members 8, 8 and 80 end angle members 9, 9. The angle members 8, 8 of each pair of them face in opposite directions, while the angle members 9, 9 face inwardly. Secured to the rear ends of the angle members 8 and 9 is a longitudinal angle member 10 whose side flange projects downwardly, and to the front of the angle members 8 and 9 there is secured a longitudinal angle member 11 whose side flange projects upwardly to hold boxes up- 85 on the frame thus formed. These longitudinal angle members 10 and 11 are preferably secured to the angle members 8 and 9 by spot-welding. Spot welded to the lower surfaces of the angle members 8, 9, 10 and 90 11 in the spaces formed between them, are flat rings 12 suitable to support baskets. (See Figures 1 and 2.)

The angle members 8, 8 of each end pair of them, receive between their vertical 100 flanges, which face each other, the straight flat rings 12 suitable to support baskets. member 4. Projecting a short distance above, and throughout the length of, the inclined part 6 of each bracket member 4 105 is a metal strip 13, the ends of which are riveted to the bracket member above and below its said inclined portion 6. (See Figure 6.)

Projecting through the down-turned 110

flanges of the angle members 8, 8 of each pair of them, between the metal strip 13 and the inclined part 6 of their respective bracket, near the ends of the latter, are 5 preferably two screw bolts 14 upon the outer ends of which nuts 15 are applied to draw the angle members 8, 8 tightly against the bracket and strip for firm support thereby. (See Figures 6 and 7.) The structure thus 10 described forms a strong and neat support for the box and basket holders 7.

Riveted or otherwise suitably secured to the middle portions of the vertical flange of each transverse bottom angle member 1, 15 and resting upon the bottom flange thereof, are two angle uprights 16, 16 which are spaced a short distance apart for a purpose to be hereinafter described. The oppositely-disposed bracket members 6, 6 at each end 20 of the display stand, terminate at their upper ends in vertical parts for attachment, by a bolt 17 and a nut 18, to their respective upright members 16, 16 as shown in Figure 6.

25 Secured to the rear sides of each pair of angle uprights 16, 16, a short distance above the bolt 17, is a triangular transverse bracket 19 which is preferably constructed of sheet metal and formed with rim flanges 30 for strength. (See Figures 3 and 8.) Countersunk holes are formed in the middle portion of each transverse bracket 19 to telescope into countersunk holes formed in the rear flanges of the uprights 16, 16, to 35 receive screw bolts 21 to the outer ends of which nuts 22 and lock washers 23 are applied. (See Figure 9.) These nuts 22 are the means of drawing the brackets 19 tightly against the uprights 16, 16, while the telescopic connection between the latter and the brackets serves to relieve the bolts 21 of the 40 full strain of supporting them.

45 Mounted upon the transverse brackets 19, 19 is a tray 24 preferably of rectangular shape and having a flat bottom 25 and perforated sides 26. (See Figures 1 and 14.) The tray bottom 25 is formed with two T slots 27, 27 through which the two sets of supports 16, 16 vertically project. (See 50 Figures 1 and 11.) A longitudinal partition 28 extends from one end of the tray to the other between the uprights 16, 16 near each end of it. The parallel flanges of each set of these uprights are secured to the 55 longitudinal partition 28 by screw bolts 29. This longitudinal partition 28 is preferably constructed of a strip of sheet metal which is bent upon itself and has formed along its bottom edges, at frequent intervals, 60 tongues 29a which are passed through holes in the tray bottom and then turned upwardly against its lower surface to assist in keeping the latter from sagging.

65 A series of transverse partitions 30 are mounted upon the tray bottom between the

longitudinal partition 28 and the sides 26 of the tray. These transverse partitions 30 on one side of the tray have spot-welded between their inner folded portions, metal strips 31 which terminate beyond the partitions in hook projections 32. The latter are adapted to be passed through vertical slots in the longitudinal partition 28 for entrance into locking recesses 33 formed in plates 34 spot-welded within the folded inner portions of the adjacent transverse partitions 30. (See Figure 10.) Before this locking connection is effected between them, the adjacent transverse partition members 30, 30 are inclined to each other, after which the locking projection 32 on one is projected through the vertical slot in the longitudinal partition 28 into the locking recess 33 in the plate 34 in the other. The entire unit is then forced downwardly to lock the transverse partitions 30, 30 firmly together against the longitudinal partition 28, after which the latter is connected to the uprights 16, 16 by the screw bolts 29.

90 Formed in the bottom 25 of the tray is a downwardly-turned rim flange 35 which enters a recess formed by a marginal band 36, that also receives the lower part of the tray side 26 which, along its upper edge, is turned downwardly and then upwardly behind its outer flap to form a strong, neat appearing rim portion. (See Figures 1 and 5.) The recessed marginal band 36 and the bottom 25 and side 26 of the tray are spot-welded together to form between them, a 95 firm connection of pleasing appearance. Formed at each end of the brackets 19 is a right angled ear 37 to which the marginal band 36 is bolted or otherwise suitably secured. (See Figures 1 and 8.)

100 A tray 38 similar to, though smaller than, the tray 24 is supported above the latter by the uprights 16, 16 in the same manner that the tray 24 is supported by them.

105 Secured to the top ends of the uprights 16, 16 are triangular brackets 39 which are similar to, though smaller than, the brackets 19. Bolted between the uprights 16, 16 for each bracket 39, is one end of a longitudinal supporting member 40 which projects between said brackets to support, with them, the bottom 41 of a top shelf 42. (See 110 Figures 3, 12 and 13.) The shelf bottom 41 terminates at its outer edge in downwardly turned rim flanges 43 to which there are spot-welded crimped metal strips 44 which terminate above the bottom 41 in marginal beads 45 that provide for the shelf a slightly elevated and neat marginal rim. (See Figures 1 and 4.)

115 It is thus seen that I have provided a display stand which is not only pleasing and neat in appearance, but which lends itself to economical manufacture and efficient service.

Having described my invention, I claim:—

1. In a device of the type described, the combination with base members, a pair of angle uprights projecting upwardly from each base member, a tray supported by said uprights, a longitudinal partition in said tray projecting between said uprights and secured to their parallel flanges, and a pair of oppositely disposed transverse partition members secured against said longitudinal partition member behind said uprights.
2. In a device of the type described, the combination with base members, of uprights secured to said base members, a tray, and triangular sheet metal brackets secured at their middle portions to said uprights and horizontally flanged at their edges for supporting said tray.

In testimony whereof I have hereunto set my hand this 13th day of January, 1925.

ERHARD ALLEN.
